F. J. KALTEYER

BLADE HOLDER FOR SAFETY RAZOR BLADES

Filed June 24, 1920

INVENTOR.
Federico J. Kalteyer,
BY
Frank J. Anderson,
ATTORNEY.

UNITED STATES PATENT OFFICE.

FREDERICK J. KALTEYER, OF PHILADELPHIA, PENNSYLVANIA, ASSIGNOR TO ELECTOSTROP MANUFACTURING COMPANY, A CORPORATION OF PENNSYLVANIA.

BLADE HOLDER FOR SAFETY-RAZOR BLADES.

Application filed June 24, 1920. Serial No. 391,483.

To all whom it may concern:

Be it known that I, FREDERICK J. KALTEYER, a citizen of the United States, residing in Philadelphia, in the county of Philadelphia and State of Pennsylvania, have invented certain new and useful Improvements in Blade Holders for Safety-Razor Blades; and I do declare the following to be a full, clear, and exact description of the invention, such as will enable others skilled in the art to which it appertains to make and use the same, reference being had to the accompanying drawings and to the letters and figures of reference marked thereon, which form a part of this specification.

My invention relates to blade holders for safety razor blades while being honed or stropped. It has for its object to provide novel features of construction which contribute to expedition in making the holder, and result in producing a holder strong and durable in use, and in which the blade may be readily inserted and detached and effectively clamped when in the holder. To the accomplishment of the foregoing and such other objects as may hereinafter appear the invention consists in the features hereinafter particularly described and then sought to be clearly defined by the claims, reference being had to the accompanying drawing forming part hereof and in which—

Figure 1 is a front elevation of part of a suitable sharpening device with the blade holder in position;

Figure 2 is a front view of the blade holder;

Figure 3 is a face view of a blank from which one jaw and supporting prongs of the holder are found;

Figure 4 is a face view of a blank from which the other jaw is formed; and Figures 5 and 6 are vertical sections through the jaws fulcrums.

In the drawing the numeral 1 designates a suitable sharpening device formed with an overhanging arm 2 to which the blade holder may be clamped so as to support the blade in position to be acted on by the honing or stropping rolls 3.

The letter A designates a blank from which one jaw of the holder is made, and B the blank from which the other jaw is made. The blank from which one jaw is made is formed with a tongue which receives a spring that holds one jaw to the

other and serves also to supply the pressure for clamping a blade between the jaws, and it is also formed with fulcrum bearings on which the other jaw is fulcrumed, and also formed with studs designed to enter openings usually formed in safety blades and adapted to enter openings formed in the other jaw so as to center and steady the connection between the two jaws when in closed position. The blank from which the opposite jaw is made is formed with an opening to receive the spring bearing tongue of the companion jaw; also with openings to receive the fulcrum bearings of the other jaw, and with openings to receive the steady- 60

ing and centering studs of the companion jaws. These several parts are subject to modification in details but the preferred construction is as follows. One jaw, designated by the numeral 4, is formed with upwardly extending arms or prongs 5 by which the holder may be supported from the sharpening mechanism. It is slotted to form a tongue 6 which is bent at an angle to the plane of the jaw and is formed with 65 an opening 7 which has laterally extending slots 8. The opening 7 is designed for the insertion of the legs or prongs 9 of a spring 10 having coils 11 and a loop 12, the legs or prongs of the spring spreading apart 70 after insertion through opening 7 and entering the lateral slots 8 the walls of which 75 serve as bearings for the legs or prongs so as to hold the other jaw against which the loop of the spring bears in closed relation 80

tion. The upper portion of the jaw 15 is bent at an angle to the plane of the jaw, so as to form a finger grip 20 by which the jaw 15 may be manipulated for the insertion and withdrawal of the blade from between the jaws, and is also formed with an opening 21 registering with the coils of spring 10 for the passage of the prongs of the spring and to straddle the tongue 6 when the jaw is swung open. When the jaws are formed and connected one to the other by means substantially such as described, a very efficient holder for blades in the operation of sharpening is produced; appropriate bearings for the connecting parts affording stability and firmness of bearing points is assured; and strength and durability and simplicity in use of the holder obtained.

Instead of forming the fulcrum bearings 20 so as to project from jaw 4 they may be formed to project from jaw 15 as shown in Figure 6 but the functioning of such parts is the same in both forms and therefore same reference numerals are used.

25 I have described with particularity the preferred details of the various parts but changes can be made therein and essential features of the invention retained.

Having described my invention and set 30 forth its merits what I claim is:

1. A blade holder for sharpening devices comprising oppositely disposed jaws, one jaw having a tongue formed with an opening having elongated extensions and with 35 projected fulcrum bearings, and the other jaw formed with openings to receive said bearings for fulcruming one jaw on the other, and a spring connecting the two jaws, one part of said spring bearing against one jaw and having prongs bearing in the elongated slot extensions of the tongue of the companion jaw.

2. A blade holder for sharpening devices comprising oppositely disposed jaws, one 45 jaw having a tongue formed with an elongated opening and with projected fulcrum bearings and the other jaw formed with openings to receive said bearings for fulcruming one jaw on the other, and a spring connecting the two jaws, one part of said

spring bearing against one jaw and having prongs bearing in the elongated opening of the tongue of the companion jaw and having their ends seated in perforations in the jaw.

3. A blade holder for sharpening devices comprising oppositely disposed jaws, one jaw having a tongue formed with an opening, and also with projected fulcrum bearings, and the other jaw formed with openings to receive said bearings for fulcruming one jaw on the other, and a spring connecting the two jaws, one part of said spring bearing against one jaw and having prongs bearing in the elongated opening of the tongue of the companion jaw and having their ends seated in perforations in the jaw.

4. A blade holder for sharpening devices comprising oppositely disposed jaws, one jaw having a tongue formed with an opening and also with projected fulcrum bearings, and the other jaw formed with openings to receive said bearings for fulcruming one jaw on the other, one jaw also being formed with centering bosses and the other with corresponding openings therefor, and a spring connecting the two jaws, one part of said spring bearing against one jaw and another part bearing in the tongue of the companion jaw.

5. A blade holder for sharpening devices comprising oppositely disposed jaws, one jaw having projected fulcrum bearings and the other openings to receive said bearings for fulcruming one jaw on the other, with 85 the fulcruming point close to the adjacent faces of the two jaws, and having its upper portion deflected at an angle to the plane of the jaw to constitute a finger grip for manipulating the jaw, and a spring connecting the two jaws, one part of said spring bearing against one jaw and another part having a bearing in the companion jaw.

In testimony whereof I affix my signature in presence of two witnesses.

FREDERICK J. KALTEYER.
